Erwin Kramer,

INVENTOR.

BY Robert B. Killgore,
ATTORNEY

UNITED STATES PATENT OFFICE.

ERWIN KRAMER, OF CARLSTADT, NEW JERSEY.

GARMENT-FASTENER HOLDER.

1,274,282.

Specification of Letters Patent. Patented July 30, 1918.

Application filed November 17, 1916. Serial No. 131,889.

To all whom it may concern:

Be it known that I, ERWIN KRAMER, a citizen of the United States, residing at Carlstadt, in the county of Bergen and State 5 of New Jersey, have invented certain new and useful Improvements in Garment-Fastener Holders, of which the following is a specification.

My invention relates to improvements in 10 fastening hooks and eyes for use with garments and the like and more especially to a novel means for mounting the hooks and eyes in place on strips of fabric which can be sewed or otherwise fastened to the garments.

15 My invention contemplates the use of a folded base fabric to carry the hooks and eyes and a covering or facing fabric, which may be integral or separate, to form a composite fabric which may be sewed onto the garment.

The hooks and eyes are solidly mounted on 20 the base fabric at suitable intervals and the covering fabric is then sewed down over the bases of the hooks or eyes to conceal the same and produce a neat finish with folded edges exposed on the fabric strips and with the hook and eye rivets concealed in the base fabric.

25 In the accompanying drawing Figure 1 is a face view of my improved hook and eye strip; Fig. 2 a sectional view of the structure of Fig. 1, taken on the line 2—2— and Fig. 3 a diagrammatic edge view of a modification wherein the base and facing fabrics are separate pieces instead of being integral, and a flap edge is produced on one member. Fig. 4 is an enlarged cross sectional view 30 showing more clearly how the fasteners are secured to the folded base member of the strip.

The base fabric 1 is folded at 2 so that the edge will be finished instead of raw and the hook 3 is securely riveted or otherwise 45 attached to the upper layer 4 of the base fabric. The flap 6 will conceal and cover the rivets 5. The fabric is then carried along at 7 and doubled on itself at 8 forming a finished edge and the part 9 is carried back 50 as shown in Fig. 2 with the point 10 of the hook 3 exposed. Lines of stitching 11 and 12 are then run along the laminated fabric and hold or tie the parts together.

The eye member is made in substantially

the same manner. The base fabric 13 is 55 folded at 14 and the eyes 15 are riveted or otherwise securely fastened to the upper fold 16, the part 13 concealing the rivets. The fabric is then folded over the eye at 18 and doubled back on itself at 19 with the 60 part 20 extended rearwardly. Lines of stitching 21 and 22 tie the parts of the laminated fabric together.

The parts 4 and 6 and 13 and 16 form the base fabrics and the parts 7 and 9 and 17 65 and 20 form the facing fabrics of the hook and eye sections respectively.

Instead of forming the base and facing fabrics integral they may be separate as shown in Fig. 3 in which the base fabric 70 is a piece having the part 23 folded at 24 with the upper part 25 and the facing fabric is a piece having the inner part 26 folded at 27 with the outer facing 28. These strips are then sewed together by the lines of 75 stitching as in the structure of Figs. 1 and 2 which tie the parts together.

This stitching is preferably located so that a line comes on either side of the rivets and further resists pulling strains which would 80 otherwise tend to pull the hooks and eyes out of the fabric.

By this construction the operative parts only of the hooks and eyes are exposed, the hooks and eyes themselves are securely fastened to the base fabric and the folded front edges of the base and covering fabrics present a neat and finished appearance.

The fold in the base fabric may be carried forward as shown in Fig. 3 to form a 90 flap for filling the joint between the hook and eye strips.

I claim:

1. In a garment fastener holder the combination of a strip of material folded on 95 itself to form a base fabric, fastening members secured to the upper fold of the base fabric, the strip then being reversely folded and doubled and extended partially over the fastening members to form a facing fabric 100 and stitching extending through the folded strip to hold the parts together.

2. A hook or eye fastener carrying tape consisting of base and facing members each folded inwardly at one edge, fasteners having their anchor ends rigidly secured to the folded-in portion only of one of the members, and spaced parallel rows of stitching 105

arranged on opposite sides of the anchor ends of said fasteners for securing the base and facing members together.

3. A hook or eye fastener carrying tape 5 consisting of base and facing members each folded inwardly at one edge, fasteners riveted to the folded-in portion of the base member only, and spaced parallel rows of stitching for uniting the said base and fac-

ing members at each side of the anchor ends 16 of said fasteners.

In testimony whereof I have affixed my signature in the presence of two witnesses.

ERWIN KRAMER.

Witnesses:
